ELECTRICALLY OPERATED FAN

Daniel Evan Rogers, Gravelly Hill, Birmingham,
EnglandApplication May 7, 1935, Serial No. 20,171
In Great Britain May 18, 1934

10 Claims. (Cl. 230—255)

The invention relates to an electrically operated fan of the kind generally known as an oscillating fan, but which would be more correctly described as a fan whose fan wheel has 5 simultaneous revolution and gyration, and distinctly to that kind wherein the spindle of the fan wheel, set inclined to the motor shaft, is simultaneously revolved and gyrated relative to the stationary body of the motor and from 10 the rotation of the motor shaft.

The invention provides in such a fan a combination of parts constructed, so arranged and operative that a balanced fan wheel action, smooth running, and a gyration within substantially the diameter of the fan wheel results, one 15 of the distinguishing features being that the centre of gravity of the fan wheel and spindle unit is approximately in the plane of the fan wheel itself and also approximately on the common axis of the motor shaft and the carrier 20 for the bearing of the fan wheel spindle, the combination comprising a stationary electric motor, a revolute carrier for an inclined bearing for a fan wheel and spindle unit and which carrier is mounted on the motor casing concentric to the motor shaft and is driven from 25 said shaft at a reduced speed by suitable gearing, and a combined fan wheel and spindle unit adapted to be driven from the motor shaft while 30 its spindle engages the inclined bearing of the carrier.

Further, the invention also embodies a combination wherein the fan wheel spindle has bearings in a member which is rockable upon 35 opposite trunnions of a carrier to allow of adjustment of the inclination of the fan wheel spindle relative to the axis of the motor shaft, the axis of the trunnions being across the axis 40 of the motor shaft and the centre of gravity of the fan wheel and its spindle approximately at the axis of rocking.

Further, the invention embodies a combination wherein the revolute carrier is anti-frictionally mounted on the one end of the motor 45 body to be supported therefrom and is bored out to receive the rockable bearing member for a stub spindle fixed to the rear side of the fan wheel, which spindle is also bored out to accommodate a portion of a torsional spring 50 drive operating between the end of the motor shaft and the fan wheel spindle, the borings in both carrier and spindle enabling the arrangement of the parts to be as close as possible to the adjacent end of the motor body, which is 55 also according to the invention arranged to have

applied to it the reduction gear for driving the carrier through an axial pinion at the back of the carrier and surrounding the motor shaft.

The invention in its desirable combination is represented by the accompanying drawings:— 5

Fig. 1 is a sectional elevation of substantially the entire fan, but with certain parts omitted for clearness of illustration.

Fig. 2 is a transverse section through the reduction gear arrangement of Fig. 1 on the 10 dotted lines AB.

Fig. 3 is a transverse section through the bearing of the fan wheel spindle Fig. 1, on the dotted lines CD.

Fig. 4 is a detail view of the fan wheel and 15 its spindle.

Fig. 5 is a detail view of the adjustable part 20 of the bearing for the fan wheel spindle.

Fig. 6 is a detail view of the other part of the bearing for said spindle.

Fig. 7 is a sectional view of a circular spring 25 clip.

The motor body *a* containing the motor is mounted in convenient supports, preferably so that it can be adjusted in two directions at 25 right-angles and afterwards fixed to position the general direction of operation of the fan wheel. For this purpose said body is oppositely pivoted at *a*² within a rigidly built fork *a*³ which is supported by a base *a*⁴ in a manner allowing 30 of said fork to revolve about an axis *a*⁵ directed at right-angles to the direction of pivoting *a*², the motor body therefore having substantial adjustment upon its mounting, but being fixed 35 stationary after adjustment.

The motor shaft is indicated at *c* and is driven by the armature in the usual way and extends through a gear housing *d* rigidly secured to the end of the motor body, *a*, to also provide a support for a revolute carrier *f* arranged concentric of the shaft *c* and carrying a ring *g* providing a bearing for the stub spindle *h*² of the fan wheel *h*. The carrier *f* is supported from the housing *d* by ball bearings *f*¹, and is provided on its inner end with a toothed pinion *f*² and at its outer end is bored out from the front at *f*⁴ to receive the bearing ring *g* which externally is transversely shaped as a part of a sphere, said ring being connected to the carrier *f* so as to rock within its boring *f*⁴ upon 40 opposite trunnions, *g*², *g*³, the axis of which is across the axis of the motor shaft *c*. The spindle *h*² is freely revolute within the bore *g*⁴ of the ring *g*, and is held against axial displacement by engagement of a grub screw *g*⁵ applied 45 to the rear side of the fan wheel *h*.

to the ring g to engage an annular groove h^2 of the spindle. The ring g is formed on its exterior with a number of distanced apart notches g^3 extending at right-angles to the direction of pivoting of the ring to the carrier by the trunnions, these notches to be engaged by a ball f^5 applied to the carrier f to be spring pressed into engagement with any one of the notches, a resilient band clip i , encircling the carrier f and lying over the trunnions g^2 , g^3 , pressing this ball into engagement with the notches, said band clip being movable away from the ball and trunnions for disassembling.

The motor shaft c is coupled to the fan wheel spindle h^2 by a coiled spring j operating torsionally and providing a flexible and resilient drive between the motor shaft and the spindle, the use of this spring also easing the effect of the initial torque of the motor on starting up and providing a very effective drive from the motor shaft to the spindle for inclining the axis of the fan wheel and its spindle to the axis of the shaft.

The reduction gear for driving the carrier f from the shaft c comprises a worm l fast on the motor shaft c , a worm pinion m gearing with this worm and carried upon a cross-shaft n having bearings in the housing d , a worm o fast upon said cross-shaft, a worm pinion r fast upon a short shaft s also having bearings in the housing d , and a toothed pinion t gearing with the toothed pinion f^4 , this gearing providing for the revolution of the carrier f from the motor shaft c at a very much reduced speed.

The housing d is in greater part omitted, though indicated, in Fig. 1 for the purpose of clearer illustration of the reduction gear, but same is substantially of solid cylindrical construction bolted to the facing a^6 of the motor body by bolts a^7 , a^8 , shown in Fig. 2, while the carrier f is applied to the housing d concentric with the motor shaft c by an outer face plate u clamped to said housing by screw pins u^2 one only of which is shown, the plate u therefore becoming a one-piece part of the housing but a necessarily detachable one for assembling the several parts of the gear.

From the foregoing description and drawing it will be clear that the carrier f is concentric to the motor shaft and is revolved therefrom at a reduced speed, and that the bearing ring g is rockable within the front boring of the carrier f upon the trunnions g^2 , g^3 , to varying positions held by the ball and notch engagement, such engagement determining the inclination or otherwise of the fan wheel spindle h^2 to the axis of the motor shaft, the bearing ring g being always carried round by the carrier f during the latter's revolution while at the same time the fan wheel spindle h^2 is independently rotated from the motor shaft at the same rate of speed.

It will be clear from the description with reference to the drawing that the construction of the inclined bearing for the stub spindle h^2 and the construction of the fan wheel and stub spindle as a unit and their application to each other and to the carrier f is such that the centre of gravity of the fan wheel and spindle unit is approximately in the plane of the fan wheel itself and also approximately on the common axis of the motor shaft c and the revoluble carrier f , i. e. approximately on the intersection of the axis of the trunnions with the axis of the carrier, so that the fan wheel action is a bal-

anced one ensuring smooth running and a gyration which is substantially within the diameter of the fan wheel itself.

The drawing shows three different adjustments of inclination of the fan wheel spindle h^2 in relation to the axis of the motor shaft c , the full lines of the fan blades showing the middle position and the dotted lines the two other positions, and it will be obvious that any of these positions may be obtained by the forcible rocking of the fan wheel unit and its bearing about the trunnions against the action of the spring pressed ball.

The invention includes a combination in which the inclined axis of the fan wheel spindle h^2 can be a set one without any adjustment to vary the inclination, i. e. the spring pressed ball f^5 is holding the inclination and it is only required that a fixing pin be substituted for the spring pressed ball to obtain a set position of the fan wheel spindle unit without any adjustment to vary the inclination although that represented in the drawing and described in connection therewith giving the adjustment of inclination is the most useful and desirable form.

A guard x surrounds the fan wheel and this is carried by a tubular sleeve x^2 fitting tightly over the periphery of the housing d and upon a part of the motor body to serve the useful purpose, in addition to supporting the guard, of closing said periphery and axially holding the cross-shaft n in position. With reference to this guard, it will be obvious that it should be of as small dimensions as possible, and it will be clear that the invention enables this to be so because the gyration of the fan wheel unit is substantially within the dimensions of the diameter of the fan wheel.

The coiled spring j is coupled up to the fan wheel spindle h^2 and to the motor shaft c by end members of it engaging fork extensions of the spindle and shaft.

Having now described my invention, what I claim and desire to secure by Letters Patent is:

1. An electrically operated fan combining a stationary electric motor, a gear housing forming part of the one end of the motor casing, a revoluble carrier for a fan wheel and spindle unit and which carrier is anti-frictionally mounted upon the outer end of the gear housing concentrically to the motor shaft, said carrier having within its outer end a concentric boring, a gear arranged within the gear housing to revolve the carrier at a reduced speed from the revolution of the motor shaft a part of which gear is a concentric pinion fixed to the back of the carrier, a bearing ring rockably arranged within the boring on trunnions at right-angles to the axis of the carrier and intersecting said axis, spring pressed means applied between the carrier and ring for fixing the bearing ring within the boring in adjusted position, a combined fan wheel and spindle unit whose stub spindle engages the bearing ring from the front, said stub spindle being bored out from the back, and a torsional coiled spring applied as a driving means between the motor shaft and the spindle of the fan wheel.

2. An electrically operated gyratory fan combining a stationary electric motor, a revoluble carrier mounted on the motor casing concentrically to the motor shaft and driven from said shaft at a reduced speed by gearing, an inclined bearing forming a part of the carrier and which

5 is arranged symmetrically around the axis of gyration, a combined fan wheel and stub spindle unit whose spindle engages the inclined bearing so that said unit is also arranged symmetrically around said axis of gyration, and means for driving the spindle unit from rotation of the motor shaft.

10 3. An electrically operated gyratory fan combining a stationary electric motor, a revolute carrier mounted on the motor casing concentrically to the motor shaft and driven from said shaft at a reduced speed by gearing, an inclined bearing forming a part of the carrier and which is arranged symmetrically around the axis of gyration, a combined fan wheel and stub spindle unit whose spindle is hollow and engages the inclined bearing so that said unit is also arranged symmetrically around said axis of gyration, and flexible means engaging the hollow 15 spindle for driving the unit from the motor shaft.

20 4. An electrically operated gyratory fan combining a stationary electric motor, a revolute carrier mounted on the motor casing concentrically to the motor shaft and driven from said shaft at a reduced speed by gearing, a rockable bearing forming a part of the carrier and which is arranged symmetrically around the axis of gyration and which bearing is fixable after adjustment, a combined fan wheel and stub spindle unit whose spindle engages the bearing so that said unit is also arranged symmetrically around said axis of gyration, and means for driving the spindle unit from the motor shaft.

25 5. An electrically operated gyratory fan combining a stationary electric motor, a revolute carrier mounted on the motor casing concentrically to the motor shaft and driven from said shaft at a reduced speed by gearing, a rockable bearing forming a part of the carrier and which is arranged symmetrically around the axis of gyration, a combined fan wheel and stub spindle unit whose spindle is hollow and engages the inclined bearing so that said unit is also arranged symmetrically around said axis of gyration, and flexible means engaging the hollow 30 spindle for driving the unit from the motor shaft.

35 6. An electrically operated gyratory fan combining a stationary electric motor, a revolute carrier arranged on the motor casing concentric to the motor shaft and driven from said shaft at a reduced speed by gearing, said carrier having within its outer end a concentric boring, a bearing ring rockably arranged within the boring 40 on trunnions at right angles to the axis of the carrier and intersecting said axis and which bearing is arranged symmetrically around the axis of gyration, a combined fan wheel and stub spindle unit whose spindle engages the rockable bearing ring so that said unit is also arranged symmetrically around said axis of gyration, and means for driving the spindle unit from the motor shaft.

45 7. An electrically operated gyratory fan combining a stationary electric motor, a revolute carrier mounted on the motor casing concentrically to the motor shaft and driven from said shaft at a reduced speed by gearing, said carrier having within its outer end a concentric boring, a bearing ring rockably arranged within the boring on trunnions at right angles to the axis of the carrier and intersecting said axis and which bearing is arranged symmetrically around the axis of gyration, a combined fan wheel and stub spindle unit whose spindle is hollow and engages the rockable bearing ring so that said unit is also arranged symmetrically around said axis of gyration, and flexible means engaging the hollow 50 spindle for driving the unit from the motor shaft.

55 8. An electrically operated gyratory fan combining a stationary electric motor, a revolute carrier mounted on the motor casing concentrically to the motor shaft and driven from said shaft at a reduced speed by gearing, a rockable bearing forming a part of the carrier and which is arranged symmetrically around the axis of gyration, means spring pressed into action for snap fixing the bearing ring in adjusted position, a combined fan wheel and stub spindle unit whose spindle engages the bearing so that said unit is also arranged symmetrically around said axis of gyration, and means for driving the spindle unit 60 from the motor shaft.

65 9. An electrically operated gyratory fan combining a stationary electric motor, a revolute carrier mounted on the motor casing concentrically to the motor shaft and driven from said shaft at a reduced speed by gearing, said carrier having within its outer end a concentric boring, a bearing ring rockably arranged within the boring on trunnions at right angles to the axis of the carrier and intersecting said axis, which bearing is arranged symmetrically around the axis of gyration, means spring pressed into action for snap fixing the bearing ring in adjusted position, a combined fan wheel and stub spindle unit whose spindle is hollow and engages the inclined bearing so that said unit is also arranged symmetrically around said axis of gyration, and flexible driving means engaging the hollow spindle for driving the unit from the motor shaft.

70 10. An electrically operated gyratory fan combining a stationary electric motor, a revolute carrier mounted on the motor casing concentrically to the motor shaft, gearing mounted on the motor casing to drive said carrier from the motor shaft at a reduced speed, an inclined bearing forming a part of the carrier and which is arranged symmetrically around the axis of gyration, a combined fan wheel and stub spindle unit whose spindle engages the inclined bearing so that said unit is also arranged symmetrically around said axis of gyration, and means for driving the spindle unit from the motor shaft.

DANIEL EVAN ROGERS.
